DESIGN FOR A GUN CHARGER

Carl J. Schuler, Los Angeles, Calif., assignor to
Interstate Aircraft and Engineering Corp., a
corporation of California

Application September 4, 1944, Serial No. 115,186

Term of patent 14 years

(Cl. D30—1)

To all whom it may concern:

Be it known that I, Carl J. Schuler, residing at Los Angeles, in the county of Los Angeles and State of California, a citizen of the United States, have invented a new, original, and ornamental Design for Gun Charger, of which the following is a specification, reference being had to the accompanying drawing, forming part thereof.

In the drawing:

Fig. 1 is a side elevational view of a gun charger embodying my new design;

Fig. 2 is a bottom plan view of the gun charger shown in Fig. 1;

Fig. 3 is an end view of the gun charger, looking at the lefthand end of the gun charger; and

Fig. 4 is a view of the opposite end of the gun charger.

I claim:

The ornamental design for a gun charger, as shown.

CARL J. SCHULER.
